CIRCUIT CONTINUING DEVICE

Harry A. Douglas, Bronson, Mich.

Application May 9, 1929. Serial No. 361,677

5 Claims. (Cl. 173—346)

My invention relates to circuit continuing devices and is of particular service in connection with those circuit continuing devices which are in the form of incandescent lamps, though the 5 invention is not to be thus limited.

I provide a shell within which the contact carrier is rotatable and having a slot in its side that extends crosswise of the shell, a handle extending into the shell and confined to one plane 10 of movement and having sliding connection with the shell at one end of the handle and complementary cam formations upon the shell and contact carrier forcing movement of the contact carrier lengthwise of the 15 bore of the shell as the contact carrier is turned by the handle. Where my invention is employed in conjunction with an incandescent lamp whose circuit is to be controlled by the handle, the contact carrier is inclusive of a socket for 20 the lamp, and also, of the lamp base which is separably received within the socket and which constitutes a contact carrying plug, a contact being provided upon the inner end face of the 25 plug. A spring is employed which presses against a shoulder upon the shell at one end of the spring and against a forward portion of the socket at the other end of the spring which aids in the separating movement of the contacts and which desirably cooperates with one wall of the slot in 30 confining the handle to one plane of movement, the spring desirably pressing the handle against this slot wall.

The invention will be more fully explained in connection with the accompanying drawing in 35 which Fig. 1 is a side view of the preferred embodiment of the invention, portions being shown in section; Fig. 2 is a view, on a larger scale, taken at right angles to the direction in which Fig. 1 is taken, parts being broken away and 40 other parts being shown in section; Fig. 3 is a sectional view on line 3—3 of Fig. 1; Fig. 4 is a sectional view on line 4—4 of Fig. 3; Fig. 5 is a sectional view on line 5—5 of Fig. 4; and Fig. 6 is a sectional view on line 6—6 of Fig. 3.

45 The structure illustrated is inclusive of a generally cylindrical shell 1 which is reduced at one end and there threaded to receive a nut 2 which is employed to clamp the shoulder 3 of the shell in assembly with a support 4, which support 50 may be the dash-board of an automotive vehicle. I have shown a distance preserving hollow washer 6 which may be interposed between the nut and the support. The shell constitutes a contact carrier to which end a contact carrier 55 ring 7, of insulation, is assembled with the rear

end of the shell. This ring of insulation is provided with a metallic bushing 8 that receives a metallic sleeve 9 which is slideable in the bore of the bushing. A circuit continuing conductor 10 enters the sleeve 9 and is electrically connected 60 with a contact button 11 at the inner end of the sleeve. A coil spring 12 surrounds the portion of the sleeve that is within the casing. One end of this spring presses against the bushing and the other end presses against the contact button whereby this button is forwardly pressed. The limit to which the button may be forwardly pressed is determined by the flange 13 which is provided upon the rear end of the sleeve 9, this flange being adapted for abutting engagement 65 with the bushing. A contact 14, which is complementary to the contact 11, is provided upon a plug 15. This plug, in the embodiment of the invention illustrated, also constitutes a base of 70 an incandescent lamp. A filament 16 of this lamp is located within the glass bulb 17 and has one terminal connected with the contact button 14. The other terminal of this filament is connected with a metallic sheath 15'. The lamp socket 18 is provided with diametrically opposite bayonet channels 19 which receive the bayonet pins or projections 20 that are provided upon and project laterally from the plug 15. These bayonet pins or projections are receivable 75 at the front ends of the bayonet channels and pass along the bayonet channels longitudinally of the structure until the inner ends of the channels are reached whereafter the plug is turned to bring the said bayonet projections into the bayonet seats. The lamp socket and lamp bore 80 thus collectively constitute a contact carrier.

A coil spring 21 surrounds the lamp socket and at its inner end presses in part upon the shoulder 3 through the intermediation of a member presently described. The outer end of the spring presses against the flange 22 which is formed upon the front end of the socket. When the socket is moved forwardly the contacts 11 and 14 are separated. When the socket is moved inwardly these contacts are engaged, the contact 11 then moving slightly to the rear against the force of the spring 12.

The handle 23 projects through a slot 24 which is formed crosswise of and through the shell. The portion of the handle upon the exterior of the shell is suitably formed for engagement by a thumb and finger. The inner end of the handle is desirably in the form of a ring 25 which surrounds the socket. Two prongs 26 and 27 are formed upon the inner end of the handle, these

prongs being radial continuations of the ring 25. Said prongs embrace a rib or finger 28 provided upon the lamp socket and separated at its sides from the lamp socket by the slots or channels 29 and 30 and the continuation of the bayonet channel 19 that extends beyond the seats for the bayonet projections 20. When the handle is turned it presses upon the rib or finger 28 to turn the lamp socket in one direction or the other. I employ two prongs 26 and 27 since neither slots 29 or 30 has longitudinal walls which are long enough to permit of the use of but one prong, the slot 29 terminating materially short of the rear end of the socket and one wall of the slot 30 being discontinued by reason of the transverse continuation of the bayonet channel 19 into this latter channel. However, I do not wish to be limited to the employment of two prongs.

20 The finger or rib 28 and the channels or slots 29 and 30 that define this rib extend lengthwise of the lamp socket. The inner end of the spring 21 presses upon the handle in the region of the slot 24 and presses the handle against the rear transverse wall of the slot 24, the spring cooperating with this slot wall to confine the handle to a plane of rotation which is preferably perpendicular to the axis of the shell. Diametrically opposite from the slot 24 the spring 21 presses the handle against the shoulder 3. The rotary movement that is imparted to the lamp socket by turning the handle also causes movement of the socket along its axis through the cooperation of cam formations upon the shell and socket. The cam formation upon the socket is desirably inclusive of two bayonet slots or channels, each having a branch 31 that is inclined to the axis of the socket and a branch 32 that is desirably perpendicular to the axis of the socket. A seat 33 is provided at the rear end of each channel 31 and a seat 34 is provided in each channel branch 32. The cam formation upon the shell is desirably inclusive of two bayonet projections or pins 35 which may be inwardly punched portions of said shell. When the lamp socket is turned by the handle the aforesaid cam formations upon the shell and socket cause the socket to move lengthwise of the shell. As the socket moves lengthwise of the shell, the rib or finger 28 moves lengthwise of the shell and between the prongs 26 and 27. The shell thus moves with the handle in the rotary direction of movement of the handle but with respect to the handle longitudinally of the shell. The handle and lamp socket are thus in splined connection. When the handle is turned to full extent in one direction, the seats 33 are positioned to receive the bayonet projections 35, the lamp circuit being then opened. When the handle is turned to its full extent in the other direction, the seats 34 are positioned to receive these bayonet projections, the lamp circuit being then closed. In order to limit the turning movement of the socket to prevent the bayonet projections 35 from being carried beyond the seats 34, I provide an inwardly projecting tongue 36 upon the shell, this tongue being positioned to engage the corner portion 37 of the lamp socket when the parts 34 are brought into register with the parts 35.

70 Referring more particularly to Fig. 4 a groove 38 is pressed into the lamp socket longitudinally thereof to receive the bayonet projection 35 that appears uppermost in this figure, in the process of assembly. A similar groove 39 is pressed into the lamp socket longitudinally opposite the

groove 38 to receive the remaining bayonet projection 35 and the prong 27 upon the handle, in the process of assembly. In the process of assembly the thumb piece 23 of the handle is initially in the plane of the ring 25. The entire handle is inserted within the bore of the shell, the thumb portion 23 of the handle thereafter being projected outwardly through the slot 24, the ring being suitably positioned for this purpose. When the ring is brought to its position transverse of the shell the thumb piece 23 is turned by pliers, at right angles to the plane of said ring. The lamp socket is next inserted and suitably manipulated to bring the bayonet projections 35 into the bayonet channels 31, 32 and the rib or finger 28 between the prongs 26 and 27.

80 The device may be constituted a cowl lamp structure by the provision of a bead 40 upon and about midway of the larger portion of the shell to afford a shoulder to limit the extent to which the cylindrical cowl 41 may be slipped upon the shell and to prevent the cowl from reaching the handle. This cowl may have a side opening 42 in the part thereof that projects forwardly beyond the shell and through which opening the light from the lamp may pass. The cowl desirably turns upon the shell so that the position of the opening may be adjusted to determine the direction in which the light flows.

85 Changes may be made without departing from the invention.

90 Having thus described my invention, I claim:

1. The combination with a shell; of a socket surrounded by the shell and movable along the bore thereof; a spring pressing upon said socket; a plug within and carried by said socket; complementary contacts respectively disposed upon the plug and shell; and a handle passing laterally through the shell and having connection with the socket to turn the socket, said shell and socket having interengaging cam formations forcing longitudinal movement of the socket as the socket is turned by the handle, said contacts being positioned to be engaged when the socket is moved longitudinally of the shell in one direction and to be separated when the longitudinal movement of the socket is reversed, wherein the shell has a guiding slot extending substantially at right angles to the shell axis and through which the handle projects and by a wall of which the handle is guided.

100 2. The combination with a shell; of a socket surrounded by the shell and movable along the bore thereof; a spring pressing upon said socket; a plug within and carried by said socket; complementary contacts respectively disposed upon the plug and shell; and a handle passing laterally through the shell and having connection with the socket to turn the socket, said shell and socket having interengaging cam formations forcing longitudinal movement of the socket as the socket is turned by the handle, said contacts being positioned to be engaged when the socket is moved longitudinally of the shell in one direction and to be separated when the longitudinal movement of the socket is reversed, wherein the shell has a guiding slot extending substantially at right angles to the shell axis and through which the handle projects and by a wall of which the handle is guided and wherein the spring presses the handle upon the guiding wall of the slot.

105 3. The combination with a shell reduced at one end to form a shoulder; of a socket movable therewithin rotatively and longitudinally; a

spring pressing against said shoulder at one end and at its other end pressing said socket away from the shoulder; a handle passing laterally through the shell and rotatable with the socket, 5 said handle being interposed between the spring and shoulder and the spring pressing upon the handle to define the plane of rotation of the handle.

4. The combination with a shell; of a member 10 movable therein rotatively and longitudinally; a handle splined to rotate the member, said member and handle being relatively movable longitudinally of the member; a slot in the shell extending at right angles to the shell axis through 15 which the handle projects and by which the handle is guided in a plane of rotation at right angles to the shell axis; and interengaging cam formations on the shell and member forcing longitudinal movement of the member with respect to the shell and handle as the member is 20 rotated by the handle.

5. The combination with a shell; of a socket movable therewith rotatively and longitudinally; an annular handle surrounding the socket and splined therewith to rotate the socket, said socket and handle being relatively movable longitudinally of the socket; a slot in the shell through which the handle projects, said handle being guided by a wall of said slot extending substantially at right angles to the shell; a spring surrounding the socket and pressing the handle upon said wall, said spring also engaging the socket to press it away from said wall; and interengaging cam formations on the shell and socket forcing longitudinal movement of the socket in the shell in one direction against the pressure of said spring as the socket is rotated by the handle and in the opposite direction with the cooperation of said spring.
